UNITED STATES PATENT OFFICE.

JASPER SCOTT, OF ARBUTUS, WEST VIRGINIA, ASSIGNOR OF ONE-HALF TO B. H. NEWCOMER, OF SPRING HILL, WEST VIRGINIA.

SELF-DUMPING APPARATUS.

961,652.

Specification of Letters Patent. Patented June 14, 1910.

Application filed February 16, 1909. Serial No. 478,276.

To all whom it may concern:

Be it known that I, JASPER SCOTT, a citizen of the United States, residing at Arbutus, in the county of Kanawha and State of West Virginia, have invented certain new and useful Improvements in Self-Dumping Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in automatic dumping apparatus and comprises various details of construction, combinations and arrangements of parts which will be hereinafter fully described and then specifically defined in the appended claims.

I illustrate my invention in the accompanying drawings, in which:—

Figure 1 is a vertical sectional view through the trestle showing the parts of the dumping apparatus in readiness to be actuated by the wheel of a car. Fig. 2 is a sectional view showing the parts set to engage and hold a car to be dumped. Fig. 3 is a top plan view of the apparatus. Fig. 4 is a sectional view showing the apparatus in end elevation. Fig. 5 is a sectional view showing the apparatus holding the car in a position in which it is dumped. Fig. 6 is a detail perspective view of a part of the invention. Fig. 7 is a detail perspective view showing the parts illustrated in Fig. 6 disassembled. Fig. 8 is a detail view of portions of the tracks D' and D³ and the member H. Fig. 9 is a perspective view of the structure shown in Fig. 8, showing the under construction of that portion of the machine, and Fig. 10 is a detail perspective view of the feature shown in Figs. 8 and 9 showing the member H removed.

Reference now being had to the details of the drawings by letter, A designates the standards of the trestle supporting the tracks B upon which the wheels C of a car travel. Fixed inclined extension tracks are designated in the drawings by letters B', B¹ which tracks are supported by the standards B², and D' designates the tracks which are pivotally mounted upon the

pivotal rods D², and D³ designates tracks which are pivotally connected to the tracks D' by means of the pivot pins D⁴. Said tracks D³ are provided with laterally extending flanges D⁵ and their ends overlap the ends of the tracks B' in the manner shown clearly in Fig. 3 of the drawings.

E, E designate inclined tracks, only one of which, however, shows in Fig. 6 of the drawings, the other being parallel therewith, the two inclined tracks adapted to receive a car as it rolls down the inclined tracks B' and switches thereon. Said tracks E are upwardly turned in order to limit the movement of the car as it turns by gravity down the inclined tracks B', the car being switched in any suitable manner not shown.

Fastened to the track D' is a bar F to which a curved bar F' is fastened, and G designates a counter-balanced weight which is fastened to the bar F' and serves to normally return the track D' to its horizontal position after a car has been dumped. Pivotally mounted adjacent to each track D' upon the pivot pins D² are the bars H, the forward ends H⁴ of which are upwardly curved, forming hooks H² and fastened to each bar H is a rod H', to the lower ends of which are secured a weight H⁵ which operates with the bars H to return the bars H² to their normal positions, said bars H being connected to the bar O⁷ by means of the links H⁶. Each of said bars H has a rocker arm H⁷, tending to contact with the wheel to start the car backward after having been dumped, it being understood that the weight H⁵ will be sufficient for this purpose.

Referring to Fig. 3 of the drawings will be noted a plate K which is fastened to the two tracks D', said plate having a slot therein for the reception of the hook N formed at the upper end of the pivotal bar N', which latter is mounted upon the pin N². A release lever, designated by letter O, is fulcrumed upon the bracket member O⁵ and is pivotally connected by means of a pin O⁶ with a lever O⁷, pivoted on a pin O', and O² designates a link pivoted at one end to the lever O⁷ and its other end to the bar H, there being one of said bars H positioned adjacent to each sectional track D', so that the curved portion H⁴ thereof will contact with the wheel of the car to be dumped when in the position shown in Fig. 110

5 of the drawings and prevent the car from further forward movement while being dumped. The upper edge of each bar O has notches O⁸ and adapted to be engaged by a 5 pin O⁹ carried by the bracket member and serving to limit the longitudinal movement of said bar in one direction. A spring O¹⁰ is fastened at one end to the curved portion of the bar O and at its other end to the 10 bracket member O⁵ and tends to hold the bar O at its farthest limit in one direction. A chain Q is fastened at one end to the pivot O⁶ and at its other end to the bar N'. Mounted upon a pivot pin L is a lever L' 15 to which a bar L² is pivoted, which in turn is pivotally connected to a lever I, the end of which is provided with two jaws I', shown clearly in Figs. 6 and 7 of the drawings, each of said jaws being pivotally mounted upon a pin I², and integral fingers I³ project from said jaws and are adapted to register with apertures in the bracket I⁴ which supports said jaws. The bracket arms M are connected by means of a ratchet bar 20 M' designed to be engaged by said lever L' to hold the same in adjusted position. Said curved bar F' is provided with perforations S, shown clearly in Fig. 7 of the drawings, which are designed to be engaged by the 25 fingers I³ for the purpose of holding said bar F' in a fixed position. In order to regulate the dumping for any weight of car, apertures T are formed at intervals and through which the pins T' are passed.

30 35 In operation, the parts of the apparatus are normally positioned as shown in Fig. 1 of the drawings, in which the rear upwardly turned end of the releasing bar O projects above the upper surfaces of the tracks B and in the paths of the wheels which travel upon one of the tracks. As the car wheel strikes the portion of the bar projecting above the track, said bar will be depressed, releasing the pin O⁹ from the notch O⁸ in said bar, it 40 being noted that the notched bar is normally held through the pin by means of the spring O¹⁰ holding the same frictionally. Immediately upon releasing the pin O⁹ from the notch, the weight H⁵ which is connected by 45 means of the curved rods H' with the members H, will cause the ends of the members adjacent to the approaching car to tilt down and the curved ends H⁴ to be thrown up to the position shown in Fig. 2 of the 50 drawings to form a stop to the forward movement of the car by said concaved portions coming against the circumferences of the forward wheels. As the concaved end of the member H tilts upward, the releasing 55 bar O will be jerked forward by the link connection with said member H and will remain in such position until the car is dumped. Simultaneously with the forward movement of the releasing bar O, the catch 60 65 N will be released from the rear end of the

platform upon which the tracks D' are mounted, said catch N being actuated by means of the chain connection between the same and the pivot O⁶. When it is desired to allow the car to dump, the operator, by throwing the lever L', will disengage the gripping jaws I³ which coöperate with the bracket member shown in Fig. 6 of the drawings to frictionally hold the curved bar F' which is connected to the tilting platform upon which the tracks D' are mounted. 70 The weight of the car, the forward movement of which is arrested by the concaved ends H⁴ of the members H, will cause the platform and tracks D' to tilt and the car to dump. As the platform tilts in the dumping operation of the car, the rockers D² will rock on their bearing plates in the manner shown in Fig. 8 of the drawings. As the tracks and platform tilt, the forward concaved ends H⁴ of the members H will tilt 75 down and the releasing bar O will be thrown upward to its normal position so that its curved end will project above the tracks B and, when reaching such position, the pin O⁹ will engage the notch O⁸ and hold said 80 releasing bar in such position until ready for operation by a succeeding car to be dumped. When the releasing bar O is held in the position shown in Fig. 1 of the drawings, the member H will be held with its 85 concaved end below the tracks D' with the weight H⁵ held in suspension ready to tilt the member H when the bar O is released. After the car is dumped, the weight G fastened to the bar F' coöperates with the 90 rocker arms to return the tracks D' and the platform to their normal positions, after which the empty car may be started down the inclined tracks D' and another car 95 brought forward and dumped in a similar 100 manner.

What I claim to be new is:—

1. An automatic dumping apparatus, comprising a trestle, a fixed track thereon, a pivotal track section, a movable release lever adapted to be actuated by the moving car, pivotal hooked bars adapted to be thrown into the path of the wheels of a car to be dumped, pivotal connections between said bars and releasing levers, lever-actuated means for allowing a car to dump upon said tilting track section, a pivotal hook normally holding said tilting section in a fixed position and actuated by the movement of said releasing lever, and counter-balanced mechanism for returning the track section to its normal position, as set forth. 110 115 120

2. An automatic dumping apparatus, comprising a trestle, a fixed track thereon, a pivotal track section, a movable release lever adapted to be actuated by the moving car, pivotal counter-balanced bars having curved portions adapted to be thrown into the path of the wheels of the car to be 125 130

dumped, pivotal link and lever connections between said bars and releasing lever, a pivotal hook adapted to normally hold said track section in a fixed position, and means for releasing said hook as said releasing lever is actuated in one direction, as set forth.

3. An automatic dumping apparatus, comprising a trestle, a fixed track thereon, a pivotal track section, a movable release lever adapted to be actuated by the moving car, pivotal counter-balanced bars having curved portions adapted to be thrown into the path of the wheels of the car to be dumped, pivotal link and lever connections between said bars and releasing lever, a pivotal hook adapted to normally hold said track section in a fixed position, and a chain connecting said hook and pivotal lever, as set forth.

4. An automatic dumping apparatus, comprising a trestle, a fixed track thereon, a pivotal track section, a movable release lever adapted to be actuated by the moving car, pivotal counter-balanced bars having curved portions adapted to be thrown into the path of the wheels of the car to be dumped, pivotal link and lever connections between said bars and releasing lever, a pivotal hook adapted to normally hold said track section in a fixed position, a chain connecting said hook and pivotal lever, a counter-balanced bar connected to the pivotal track section, a lock for engaging said weighted bar, and lever for releasing said lock, as set forth.

5. An automatic dumping apparatus, comprising a trestle, a fixed track thereon, a pivotal track section, a movable release lever adapted to be actuated by the moving car, pivotal counter-balanced bars having curved portions adapted to be thrown into the path of the wheels of the car to be dumped, pivotal link and lever connections

between said bars and releasing lever, a pivotal hook adapted to normally hold said track section in a fixed position, a chain connecting said hook and pivotal lever, a counter-balanced bar connected to the pivotal track section, a pivotal lever, a bar connected thereto and provided with jaws, and fingers upon said jaws adapted to engage apertures in said counter-balanced bar which is pivotally connected to the tilting track section, as set forth.

6. An automatic dumping apparatus, comprising a trestle, a fixed track thereon, a pivotal track section, a movable release lever adapted to be actuated by the moving car, bracket members supporting said lever, notches in the upper edge of the latter, pins carried by said bracket member and adapted to engage said notches, one end of the releasing lever positioned in the path of the wheels of a car to be dumped, pivotal counter-balanced levers having curved ends, connections between said bars and releasing lever, a releasing hook connected to said tilting bars, a spring connected to the releasing lever and to said bracket member, as set forth.

7. In combination with a trestle, a pivotal track section having a slotted plate, a pivotal hook normally engaging the edge of said slot, a movable spring-pressed releasing lever having curved ends extending above said track and in the path of a car to be dumped, pivotal bars having hooked ends, connections between said releasing lever and bars and hook, rocker arms upon said tilting bars, and a counter-balanced weight connected to the latter, as set forth.

In testimony whereof I hereunto affix my signature in the presence of two witnesses.

JASPER SCOTT.
